UNITED STATES PATENT OFFICE.

FREDERICK W. OSBORNE, OF BALLARDVALE, ASSIGNOR TO THE MAGEE FURNACE COMPANY, OF BOSTON, MASSACHUSETTS.

DESIGN FOR A BASE FOR COOKING-STOVES.

SPECIFICATION forming part of Design No. 23,069, dated February 13, 1894.

Application filed January 11, 1894. Serial No. 496,544. Term of patent 14 years.

To all whom it may concern:

Be it known that I, FREDERICK W. OSBORNE, a citizen of the United States, residing at Ballardvale, in the county of Essex and State of Massachusetts, have invented and produced a new and original Design for a Base for Cooking Stoves and Ranges, of which the following is a specification, reference being had to the accompanying drawing, forming a part of this specification in explaining its nature, in which the figure is a view in perspective of the base, showing my design.

The base is intended as a support for a cooking stove or range. The principal elements of the design are found in the corners, in the immediate sections between the corners, and in the stove legs, and they embrace ornamental features upon the surface of these parts as well as edge configuration.

The base has along its top edge extending around the corners a number of parallel beads upon an outwardly rounded section. This section is lettered a . Below this beaded section, there is another minor beaded section a' , parallel with the first. This section also extends about the corners. There extends between the corners forming the lower portions of the intermediate sections the plain border a'' , which has a ribbed lower edge, and the ends a^4 of which are curved where they join the legs into a sort of volute curve, and from which extend outwardly the oppositely curved bracket-like or outwardly curved sections a^5 . This lower border upon the front of the stove has extending upward sections a^6 which form between the lower border and the bead work a central panel a^7 . This panel has extending from a center a^8 a number of diverging curved figures the ends of which

are turned inwardly upon the inner edge of the border.

The ends of the base between the corners are unprovided with a central panel. The corners b each have a rather heavy ornamental effect produced by a representation of a section of a conventional acanthus leaf extending upward from the lower edge of the corner above the stove leg and curved outwardly and inwardly, the edge of a section overlapping the bead-work a^2 . An acanthus spray b' extends from the central figure at the corner upon each side. At the front this spray is separated by the panel above described. The legs c have at their upper edge horizontal fluted and bead-work surmounting a panel having the upper edge c' , the curved side edges c^2 extending to the horizontal sections c^3 from which the border sweeps down to the base c^4 . Across the upper part of this panel there is a representation of two sprays c^5 united at the center, extending horizontally in opposed relation to each other.

Having thus fully described my invention, I claim and desire to secure by Letters Patent of the United States—

1. The design for the cooking stove and range base, substantially as herein described and shown.
2. In a design for a cooking stove and range base as herein described and shown, the stove leg.
3. In a design for a cooking stove and range base as herein shown and described, the base corners.

FREDERICK W. OSBORNE.
